UNITED STATES PATENT OFFICE.

CHARLES E. DANIELS, OF ATCHISON, KANSAS.

PISTON-RING-FITTING APPARATUS.

Application filed February 14, 1924. Serial No. 692,773.

To all whom it may concern:

Be it known that I, CHARLES E. DANIELS, citizen of the United States, residing at Atchison, in the county of Atchison and 5 State of Kansas, have invented certain new and useful Improvements in Piston-Ring-Fitting Apparatus, of which the following is a specification.

This invention relates to an improvement 10 in apparatus for dressing or milling the ends of piston rings which are used on the pistons of gas engines, steam engines, compressors, etc.

Heretofore, the practice has been to individually file the ends of the rings and individually fit said rings to the piston. This, of course, is a very slow and tedious operation, and furthermore, there is no certainty that all of the rings of a given piston 20 will be fitted in a uniform manner.

One of the principal objects of my invention is to provide an apparatus whereby the ends of the piston rings may be milled 25 a predetermined amount and thereby insure a uniform fitting of all of the rings for the particular piston.

Another object of the invention is to provide an apparatus for milling the ends 30 of piston rings of different sizes and to insure the accurate milling of the ends of the rings regardless of the size of ring being milled.

Another object of the invention is to provide an apparatus of the character described in which ends of the piston rings 35 may be milled expeditiously and with a minimum amount of labor.

With the above and other objects in view 40 which will more readily appear as the nature of the invention is better understood, the same consists in the novel construction, combination and arrangement of parts hereinafter more fully described, illustrated and claimed.

Preferred and practical embodiments of 45 the invention are shown in the accompanying drawings, in which:

Figure 1 is a top plan view of a milling apparatus constructed in accordance with 50 my invention.

Figure 2 is a bottom plan view thereof, the base plate being removed.

Figure 3 is a detail sectional view taken 55 on the line 3-3 of Figure 1.

Figure 4 is a detail sectional view taken 55 on the line 4-4 of Figure 1.

Figure 5 is a side elevation showing a modified form of milling tool.

Figure 6 is a horizontal sectional view taken on the line 6-6 of Figure 5 and 60 looking in the direction of the arrows, and

Figure 7 is a detail sectional view taken on the line 7-7 of Figure 1.

Like reference numerals designate corresponding parts throughout the several figures of the drawings.

In carrying out my invention, I provide a base plate A which supports a table B. The table supports a plurality of radially movable clamping jaws C which are arranged about a circle for receiving therebetween a piston ring D. These jaws are moved inwardly or outwardly simultaneously in radial directions through the medium of a cam plate E which is actuated by a 75 hand lever F. Also mounted on the table B is a milling tool G which is operated by a hand crank H or other suitable means. This milling tool G is positioned between the ends of the piston ring D. The hand 80 lever F is moved in a direction to force the clamping jaws C inwardly and thereby compress the piston ring D so that the ends of the latter will engage the opposite milling surfaces of the tool G. While the milling tool G is being operated, the hand lever F is moved so as to further compress the piston ring D, thus causing both ends of the piston ring to be simultaneously milled. Carried by the table B is an adjustable stop 85 I which cooperates with the handle F to limit the movement thereof in one direction and thereby predetermine the amount of compression of the piston ring D and consequently limit the amount of metal 90 which is milled from the ends of said ring.

The form illustrated in Figures 5 and 6 is substantially the same as shown in Figures 1 to 4 and 7, except that in this second form the milling tool J is a reciprocating tool whereas the tool G shown in Figures 1 to 4 is a rotary tool.

Referring specifically to the drawings, the base plate A carries a plurality of standards 5 for supporting the table B. The table B 105 is circular in plan view and is formed with a plurality of inwardly extending radially disposed slots 6 for slidably receiving the

- clamping jaws C. A band 7 is secured to the periphery of the table B for the purpose of closing the outer ends of the slots 6. The clamping jaws C are each formed with a depending rib 8 and a head 9 forming resultant longitudinal grooves 10-10 for sliding contact with the walls of the slot 6. Depending from each rib 8 and secured thereto by a screw 11 is a curved shoe 12.
- 10 The shoes 12 of the respective clamping jaws C have sliding engagements with cam slots 13 formed in the cam plate E which is disposed below the table B and is rotatably supported therefrom by a concentrically disposed and downwardly projecting stud 14, a washer 15 and nut 16 cooperating with the stud to retain the cam plate E thereon.

The inner end of each clamping jaw C is recessed in its upper face to form a seat 17 for receiving the piston ring D. Furthermore, each clamping jaw carries an anti-friction roller 18 which is located in the recess forming the seat 17, whereby the ring 25 will contact with all of said rollers.

The cam plate E is provided with the laterally extending operating lever F for oscillating the cam plate E and thereby cause the clamping jaws C to be moved inwardly 30 or outwardly simultaneously.

In order to support either of the milling tools G or J, I have provided the table B with a pair of diametrically opposed standards 19 and 20 and these standards in turn support a pair of horizontally disposed guide rods 21-21, said rods being disposed in the same plane and arranged in spaced relation to the table B and on opposite sides of the center thereof. The milling tool G is fixed to a horizontal shaft 22 which is journaled in a carriage 23 having slideable engagement with the guide rods 21. The tool G is disposed centrally between the guide rods 21 and is therefore arranged in a radial plane relative to the piston ring D. The tool G is in the nature of a disc and the opposite faces 24-24 of said disc are respectively roughened to form milling or cutting surfaces. The tool G extends into a groove 25 formed in the upper face of the table B thereby increasing the amount of working surface of the tool in the plane containing the ends of the piston ring. The shaft 22 of the tool is extended beyond the base plate A and carries at its outer end the crank handle H.

In order to predetermine the amount of compression of the ring D and thereby limit the amount of metal milled from the ends of the ring, I have provided the adjustable stop I. This stop includes a bracket 26 which is adjustably mounted upon a track 27 concentric with the center of the cam plate E. The track 27 consists of a rail 28, 65 which is disposed in spaced relation to the

band 7 through the medium of spacing blocks 29-29. The bracket 26 is formed with upper and lower laterally extending ears 30 and 31 which receive the rail 28 and a screw 32 serves to clamp the ears 30 and 31 to said rail in any adjusted position of the bracket. The bracket 26 supports the stop I which is herein illustrated as a rod mounted for lengthwise movement through the medium of a micrometer adjusting means 33. The free end of the stop is adapted to be engaged by the operating lever F and thereby limit the movement of said lever in one direction.

Fixed to the table B and extending parallel with one of the slots 6 thereof is a scale 34 for the purpose of initially positioning the clamping jaws C to receive a given sized piston ring.

The operating tool J which is shown in Figures 5 and 6 of the drawings is a reciprocating tool and in this instance comprises a file 35 which is supported from a carriage 36 mounted for reciprocating movements on the guide rods 21. The carriage 36 is reciprocated through the medium of a crank 37, link 38 and an operating crank arm 39. The crank 37 is carried by a shaft 40 which is journaled in brackets 41-41 fixed to the guide rods 21, and fixed to the shaft 40 is a fly-wheel 42.

The operation of my invention is as follows: The operating handle F of the cam plate E is first moved so as to position the clamping jaws C to receive a piston ring of a given size, the initial position of the jaws for a given sized ring being indicated by the scale 34. The piston ring D is then positioned on the seats 17 of the clamping jaws C with the ends of the ring arranged on opposite sides of either of the milling tools G or J. The tool G is then rotated or the tool J reciprocated, and simultaneously the operating handle F of the cam plate is moved towards the micrometer stop I. This movement of the hand lever F oscillates the cam plate E and causes the clamping jaws C to be moved inwardly thus compressing the ring and causing the ends of said ring to bear against the opposite faces of the tool. Movement of the operating lever F is continued in the same direction until its movement is limited by the stop I. As soon as the first ring has been satisfactorily fitted to a given piston, the stop I is retained in the adjusted position. Consequently, all of the other rings for the given piston will have their ends ground the same amount and, therefore, all of the rings for a given piston will be uniformly fitted.

Without further description it is thought that the features and advantages of the invention will be readily apparent to those skilled in the art, and it will, of course, be understood that changes in the form, pro-

portion and minor details of construction may be resorted to without departing from the spirit of the invention and scope of the appended claims.

5. I claim:

1. In an apparatus for milling the ends of a piston ring, the combination of a support for said ring, of a milling tool adapted to be located between the ends of the ring, and means for progressively compressing the ring up to a predetermined point whereby the ends thereof will be pressed against the milling tool, and means for operating said tool.
10. 2. In an apparatus for milling the ends of a piston ring, the combination with a support for said ring, of a milling tool located between the ends of the ring, adjustable means for compressing the ring up to a predetermined point whereby the ends thereof will engage the milling tool, and means for operating said tool.
15. 3. In an apparatus for milling the ends of a piston ring, the combination with a support for said ring, of a milling tool located between the ends of the ring, means for compressing the ring whereby the ends thereof will engage the milling tool, a stop to limit the amount of compression of said ring, and means for operating said tool.
20. 4. In an apparatus for milling the ends of a piston ring, the combination with a support for said ring, of a milling tool located between the ends of the ring, means for compressing the ring whereby the ends thereof will engage the milling tool, an adjustable stop to predetermine the amount of compression of said ring, and means for operating said tool.
25. 5. In an apparatus for milling the ends of a piston ring, the combination with a support for said ring, of a milling tool located between the ends of the ring, means for compressing the ring whereby the ends thereof will engage the milling tool, an adjustable stop to predetermine the amount of compression of said ring, and means for operating said tool.
30. 6. In an apparatus for milling the ends of a piston ring, the combination with a support for said ring, of a milling tool located between the ends of the ring, means including an operating lever for compressing the ring whereby the ends thereof will engage the milling tool, and means for operating said tool.
35. 7. In an apparatus for milling the ends of a piston ring, the combination with a support for said ring, of a milling tool located between the ends of the ring, means including an operating lever for compressing the ring whereby the ends thereof will engage the milling tool, and a stop cooperating with said lever to limit the amount of compression of said ring, and means for operating said tool.
40. 8. In an apparatus for milling the ends of a piston ring, the combination with a support for said ring, of a milling tool located between the ends of the ring, means including an operating lever for compressing the ring whereby the ends thereof will engage the milling tool, and an adjustable stop cooperating with said lever to predetermine the amount of compression of said ring, and means for operating said tool.
45. 9. In an apparatus for milling the ends of a piston ring, the combination with a support for said ring, of a milling tool located between the ends of the ring, means including an operating lever for compressing the ring whereby the ends thereof will engage the milling tool, and an adjustable stop cooperating with said lever to predetermine the amount of compression of said ring, and means for operating said tool.
50. 10. In an apparatus for milling the ends of a piston ring, the combination with a support for said ring, of a milling tool located between the ends of the ring, means including an operating lever for compressing the ring whereby the ends thereof will engage the milling tool, and an adjustable stop cooperating with said lever to predetermine the amount of compression of said ring, and means for operating said tool.
55. 11. In an apparatus for milling the ends of a piston ring, the combination with a support for said ring, of a milling tool located between the ends of the ring, means including an operating lever for compressing the ring whereby the ends thereof will engage the milling tool, and an adjustable stop cooperating with said lever to predetermine the amount of compression of said ring, and means for operating said tool.
60. 12. In an apparatus for milling the ends of a piston ring, the combination with a support for said ring, of a milling tool located between the ends of the ring, means including an operating lever for compressing the ring whereby the ends thereof will engage the milling tool, and an adjustable stop cooperating with said lever to predetermine the amount of compression of said ring, and means for operating said tool.
65. 13. In an apparatus for milling the ends of a piston ring, the combination with a support for said ring, of a milling tool located between the ends of the ring, means including an operating lever for compressing the ring whereby the ends thereof will engage the milling tool, and an adjustable stop cooperating with said lever to predetermine the amount of compression of said ring, and means for operating said tool.

compression of said ring, and means for operating said tool.

8. In an apparatus for milling the ends of a piston ring, the combination with a table, of a plurality of clamping jaws movable radially relative to said table and adapted to receive a piston ring therebetween, a milling tool supported on the table and disposed intermediate the ends of the ring, means for simultaneously moving the clamping jaws inwardly to compress the ring whereby the ends thereof will engage said tool, and means for operating said tool.

9. In an apparatus for milling the ends of a piston ring, the combination with a table, of a plurality of clamping jaws movable radially relative to said table and adapted to receive a piston ring therebetween, a milling tool supported on the table and disposed intermediate the ends of the ring, means for simultaneously moving the clamping jaws inwardly to compress the ring whereby the ends thereof will engage said tool, means for operating said tool, and means to predetermine the inward movements of said clamping jaws.

10. In an apparatus for milling the ends of a piston ring, the combination with a table, of a plurality of clamping jaws movable radially relative to said table and adapted to receive a piston ring therebetween, a milling tool supported on the table and disposed intermediate the ends of the ring, means including an operating lever for simultaneously moving the clamping jaws inwardly to compress the ring whereby the ends thereof will engage said tool, an adjustable stop cooperating with said lever to predetermine the amount of compression of said ring, and means for operating said tool.

11. In an apparatus for milling the ends of a piston ring, the combination with a table formed with a plurality of radially extending slots, a plurality of clamping jaws respectively mounted in said slots for receiving a piston ring therebetween, a cam plate mounted for oscillatory movements below said base and formed with a plurality of cam slots, shoes respectively connected to the clamping jaws and engageable with the cam slots, a milling tool supported on the table and disposed intermediate the ends of the ring, an operating lever secured to the cam plate for oscillating the latter to move the clamping jaws inwardly to compress the ring whereby the ends thereof will engage said tool, and means for operating said tool.

12. In an apparatus for milling the ends of a piston ring, the combination with a table formed with a plurality of radially extending slots, a plurality of clamping jaws respectively mounted in said slots for receiving a piston ring therebetween, a cam

- plate mounted for oscillatory movements below said base and formed with a plurality of cam slots, shoes respectively connected to the clamping jaws and engageable with 5 the cam slots, a milling tool supported on the table and disposed intermediate the ends of the ring, an operating lever secured to the cam plate for oscillating the latter to move the clamping jaws inwardly to 10 compress the ring whereby the ends thereof will engage said tool, an adjustable stop cooperating with said lever to predetermine the amount of compression of said ring, and means for operating said tool.
- 15 13. In an apparatus for milling the ends of a piston ring, the combination with a table formed with a plurality of radially extending slots, a plurality of clamping jaws respectively mounted in said slots 20 and formed with seats for receiving a piston ring, said jaws being respectively provided with anti-friction rollers for co-operation with said piston ring; a cam plate mounted for oscillatory movements 25 below said base and formed with a plurality of cam slots, shoes respectively connected to the clamping jaws and engageable with the cam slots, a milling tool supported on the table and disposed intermediate the ends 30 of the ring, an operating lever secured to the cam plate for oscillating the latter to move the clamping jaws inwardly to com-
- press the ring whereby the ends thereof will engage said tool, and means for operating said tool.
14. In an apparatus for milling the ends of a piston ring, the combination with a support for said ring, of a pair of diametrically opposed standards carried by said support, a pair of horizontally disposed guide rods fixed to said standards, a carriage supported on said guide rods, a milling tool supported by said carriage and disposed between the ends of the ring, and means for operating said tool. 40
15. In an apparatus for milling the ends of a piston ring, the combination with a support for said ring, of a pair of diametrically opposed standards carried by said support, a pair of horizontally disposed guide rods fixed to said standards, a carriage supported on said guide rods, a milling tool supported by said carriage and disposed between the ends of the ring, means for compressing the ring whereby the ends thereof will engage the milling tool, and means for operating said tool. 45
- 50
